(57) **CLAIM**

The ornamental design for a bathroom receptacle, as shown and described.

DESCRIPTION

FIG. 1 is a perspective view showing my new design for a bathroom receptacle;

FIG. 2 is a front elevational view thereof;

FIG. 3 is a rear elevational view thereof;

FIG. 4 is a right side elevational view thereof, the left side elevational view being a mirror image of FIG. 4;

FIG. 5 is a top plan view thereof; and,

FIG. 6 is a bottom plan view thereof.

The portion delineated in dashed lines form no part of the claimed design.

1 Claim, 6 Drawing Sheets
